UNITED STATES PATENT OFFICE.

HAROLD W. SHONNARD, OF MONTCLAIR, NEW JERSEY, ASSIGNOR TO ELEVATOR SUPPLIES COMPANY, INC., OF HOBOKEN, NEW JERSEY, A CORPORATION OF NEW JERSEY.

ELECTRIC BELL.

Application filed March 28, 1928. Serial No. 265,267.

This invention relates to electric bells of the kind in which the striking mechanism comprises a striker constituted as a movable magnetic element adapted to be directly influenced by the electro-magnetic element in such a manner that the striking of the bell is effected by momentum of the magnetic element acquired upon excitation of the electro-magnetic element, and damping of the bell vibrations or rebound of the striker is prevented by the combined action on the striker of gravity and that of the electro-magnetic device.

The object of the present invention is to generally improve the construction of such a bell. One of the principal improvements consists in providing a sleeve of novel construction surrounding the reciprocating magnetic coil or plunger which constitutes the striker element.

Specifically it is an object of the present invention to provide such a sleeve having a flared section near its upper end to serve as a means for restraining the movement of the sleeve in one direction, and hence assist in maintaining the striker element normally in proper position with respect to the magnetic coil constituting the actuating instrumentality.

It is a further object of the present invention to provide a certain degree of restriction of the upper opening of the sleeve, to an extent which will prevent an escape of the striker element from the said sleeve while at the same time permitting an outward movement of the striker element to an extent sufficient to produce the desired operation.

Other objects and advantages to be derived from the use of the present invention reside in the specific construction and relative disposition of the parts, as will become apparent as the description progresses, reference being had to the accompanying drawings wherein:

Figure 1 is a view in elevation of the bell as it appears in assembled and mounted position; the sounding plate appearing in phantom.

Figure 2 is a vertical sectional view taken on line 2-2, Figure 1.

Referring to the drawings, reference character 1 indicates a mounting plate on which is supported a solenoid 2 by means of a

bracket or yoke 3 embracing the said solenoid and holding it in place against the mounting board 1 by means of the screw and nut arrangements indicated at 4. This screw and nut also serve to retain the sounding plate 5 in place, in such a position that the upward travel of the solenoid plunger 6 will cause an impact therewith at the point indicated at 7^a, thereby sounding the bell. As shown the plunger 6 is provided with an upper portion of reduced diameter as indicated at 7, the purpose for which will presently appear. Also as clearly shown in Figure 1 the plunger is separated from the coil by means of the relatively thin sleeve 8 which extends through the entire length of the coil 2 and protrudes therefrom at the upper end, where it is flared outwardly to form a retaining shoulder 9. At its uppermost end it is bent inwardly in thimble fashion, as indicated at 10, so as to leave an opening just sufficient to permit the passage therethrough of the upper end 7 of the plunger 6. The plunger 6 and sleeve 8 are retained at their lower ends by the provision of a cap 11 as shown. Binding posts are shown at 13. These serve for the reception of the current conductors (not shown) which are provided for the conduction of current to the coil 2, it being understood that the circuit leading to the binding posts 13 and coil 2 will be provided with suitable circuit making and breaking means permitting the operation of the bell at will.

With the foregoing description in mind the operation is as follows:

Upon energization of the solenoid 2 by reason of the introduction of an electric current to the windings thereof by way of the conductors leading to the binding posts 13, the magnetic attraction set up will draw the plunger 6 upwardly with considerable force to cause the upper end 7 thereof to strike against the sounding plate 5 at the point indicated at 7^a. This causes a sounding of the bell. Immediately thereafter continued energization of the solenoid 2 sets up a magnetic force tending to return the plunger 6 to a central position in this magnetic field, which will be substantially the central position in the coil 2. This force, therefore, tends to immediately withdraw the plunger from contact with the sounding plate 7^a and therefore prevents any vibration or echoing

of the single sound initially produced by the first upward travel of the plunger 6.

The plunger 6, therefore, remains in a centrally disposed position with respect to the coil 2 until such time as the coil is de-energized by reason of the breaking of the circuit thereto. When such deenergization of the coil 2 occurs the plunger 6 will, due to its own weight, return to the position indicated in Figure 2.

The provision of the flared construction indicated at 9 prevents the sleeve 8 from dropping out of the coil, independently of the provision of the cap 11. The provision 15 of the inwardly bent construction indicated at 10 prevents the plunger 6 from passing outwardly any further than is permitted by the length of the portion 7 of reduced diameter. The flared shoulder at 9 furthermore 20 serves to fix the normal location of the striker element 6 relatively to the coil 2 inasmuch as it prevents further tightening of the cap 11 after the latter has been 25 screwed on sufficiently to bring the shoulder 9 tightly against the upper edge of the casing 3.

I am aware that solenoid operated bells of this general type are old but so far as I have been able to determine I am the first 30 to provide a bell of the single impact type having the novel plunger and sleeve construction herein described, together with the other features of novelty defined in the appended claim.

25 The above specification and the annexed

drawings are to be considered only as illustrative of what I deem the preferred embodiment at this time. The invention is not limited to this specific form or to any particular combination or application of the parts, but embraces all modified forms and constructions within the scope of the appended claim.

I claim:

An electric bell comprising a base plate, 45 a hollow casing secured to said base plate, a coil in said casing, a sleeve extending through said coil and protruding on opposite sides of said casing, one end of said sleeve having its edges bent inwardly, a 50 striker element movable through said sleeve and having a reduced portion forming a shoulder adapted to cooperate with said bent edges on the sleeves whereby the stroke of the striker is positively limited, a sounding plate mounted on the casing and adapted to cooperate with the striker, and means for securing the sleeve in proper position in said casing comprising an integral shoulder 55 on said sleeve bearing against one end of the casing and a cap threaded to the opposite end of said sleeve and bearing against the opposite end of the casing, whereby said shoulder may be adjustably tightened 60 against said casing.

Signed at Hoboken in the county of Hudson and State of New Jersey this 27th day of March, A. D. 1928.

65 HAROLD W. SHONNARD.
